UNITED STATES PATENT OFFICE.

CHARLES F. McEWAN, OF OAK PARK, ILLINOIS, ASSIGNOR TO HARRY D. LATHROP, OF CHICAGO, ILLINOIS.

CAN-WASHING MACHINE.

1,396,516.

Specification of Letters Patent. Patented Nov. 8, 1921.

Application filed August 25, 1919. Serial No. 319,677.

To all whom it may concern:

Be it known that I, CHARLES F. McEWAN, a citizen of the United States, and a resident of the city of Oak Park, county of Cook, 5 and State of Illinois, have invented certain new and useful Improvements in Can-Washing Machines, of which the following is a specification.

My invention relates to improvements in 10 can washing machines, and has for its object the provision of improved means for lessening the noise and shocks of the operation thereof.

Other objects will appear hereinafter.

15 The invention consists in the combinations and arrangements of parts hereinafter described and claimed.

20 The invention will be best understood by reference to the accompanying drawings forming a part of this specification, and in which,

Figure 1 is a side view of the discharge end of a can washing machine embodying my invention.

25 Fig. 2 is a partial view corresponding with Fig. 1, but showing the parts in different positions.

Fig. 3 is a partial top plan view of the device.

30 The preferred form of construction, as illustrated in the drawings, comprises the usual reversing and discharging saddle 4, pivoted at 5 in the frame of the machine and connected by a link 6 with the upper end 35 of a lever 7. The lever 7 is in turn connected by a link 8 with a rocker arm 9 on a rocker shaft 10, mounted in the frame of the machine. The rocker shaft 10 carries another rocker arm 11, having a fork 12 40 therein, arranged to engage and disengage a roller 13 on the usual reciprocating and operating member 14 of the machine.

The arrangement is such that, as the member 45 14 reciprocates in the usual manner, the roller 13 will operate into and out of the fork 12 to cause operation of the saddle 4. Fig. 2 shows the roller 13 just entering the fork 12, and it will be noticed that continued motion of the roller 13 to the right will 50 cause rocking of the arm 11, and consequently of the shaft 10 to operate the saddle 4 in the usual manner. During this operation the fork 12 will remain in constant engagement with the roller 13, thus preventing 55 overbalancing and gravity operation of the

saddle 4 to violently invert and discharge the can, thus preventing shocks and jars and lessening the noise of the operation of the machine.

The machine is operated through periodical horizontal reciprocations of the operating bar 14 which serves in the usual manner to feed the cans through the machine in inverted positions, depositing one of said cans in the saddle 4 at each movement of said bar. At the time of the deposit of each can in said saddle, the roller 13 is just in the fork 12 as indicated in Fig. 2. Further movement of the bar 14 causes said roller to travel in said fork rocking the arm 11, and inverting and discharging the can as indicated in Fig. 1. At the end of its rocking motion the saddle 4, still carrying the can, has a tendency to continue its motion under the force of gravity and the inertia or momentum of the parts so that, unless restrained, the can will be delivered with great force and violence causing considerable noise and injury to the can. This continuation of the movement of the saddle 4 and the contained can is restrained and prevented by the engagement of the fork 12 with the roller 13 preventing the same. Thus the can will be delivered gently and without undue noise or injury thereto.

While I have illustrated and described the preferred form of construction for carrying my invention into effect, this is capable of variation and modification without departing from the spirit of the invention. I, 90 therefore, do not wish to be limited to the precise details of the construction set forth, but desire to avail myself of such variations and modifications as come within the scope of the appended claims.

Having described my invention, what I claim as new and desire to secure by Letters Patent, is:

1. A can washing machine, comprising can moving means; means engaging and disengaging said moving means for operating the same; and means for holding said operating and moving means in engagement during the operation of the latter, whereby continued operation of the latter under its own inertia is prevented, substantially as described.

2. A can washing machine, comprising reversing and discharging means; means engaging and disengaging said reversing

and discharging means for operating the same; and means for holding said operating means and said reversing and discharging means in engagement during the operation 5 of the latter, whereby continued operation of the latter under its own inertia is prevented, substantially as described.

3. A can washing machine, comprising a can reversing and discharging saddle; a 10 rocker arm arranged to operate said saddle; a reciprocating operating bar; a roller on said bar; and a fork on said rocker arm arranged to engage and disengage said roller and hold said rocker arm in engagement 15 with said roller during operation of said saddle, substantially as described.

4. A can washing machine, comprising a can reversing and discharging saddle; a 20 rocker arm arranged to operate said saddle;

a horizontally reciprocating operating bar; 20 a roller on said bar; and a fork on said rocker arm arranged to assume horizontal position to engage and disengage said roller, said fork being of sufficient length to permit of movement of said roller within said fork 25 and arranged to assume substantially vertical position at the termination of movement of said saddle, whereby continued operation of said saddle under its own inertia is prevented, substantially as described. 30

In testimony whereof I have signed my name to this specification in the presence of two subscribing witnesses.

CHARLES F. McEWAN.
